UNITED STATES PATENT OFFICE.

FRANK J. KRISTOFER AND HOWARD L. FISCHER, OF ST. PAUL, MINNESOTA,
ASSIGNORS TO BROWN & BIGELOW, OF ST. PAUL, MINNESOTA, A CORPOR-ATION OF MINNESOTA.

DESIGN FOR A DESK-TRAY.

56,929.

Specification for Design.

Patented Jan. 18, 1921.

Application filed June 10, 1920. Serial No. 388,035. Term of patent 7 years.

To all whom it may concern:

Be it known that we, FRANK J. KRISTOFER and HOWARD L. FISCHER, citizens of the United States, residing at St. Paul, county of Ramsey, and State of Minnesota, have invented a new, original, and ornamental Design for Desk-Trays, of which the following is a specification, reference being had to the accompanying drawing, forming part thereof.

Fig. 2 is a front elevation of the same.

Fig. 3 is an end elevation of the desk tray.

We claim:

The ornamental design for a desk tray as shown.

FRANK J. KRISTOFER.
HOWARD L. FISCHER.
